UNITED STATES PATENT OFFICE

149,110

DESIGN FOR A MULTIPLE CLOTHESPIN BLOCK

William T. Christmas, University City, Mo., as-
signor to The Wallace Corporation, St. Louis
County, Mo., a corporation of Missouri

Application May 29, 1947, Serial No. 139,369

Term of patent 14 years

(Cl. D17—6)

To all whom it may concern:

Be it known that I, William T. Christmas, a citizen of the United States and a resident of University City, in the county of St. Louis and State of Missouri, have invented a new, original, and ornamental Design for a Multiple Clothespin Block, of which the following is a specification, reference being had to the accompanying drawing, forming part thereof.

Fig. 1 is a top plan view of a multiple clothespin block, showing my new design,

Fig. 2 is a side elevational view,

Fig. 3 is an end elevational view; and

Fig. 4 is a perspective view of an individual clothespin.

I claim:
The ornamental design for a multiple clothespin block, substantially as shown.

WILLIAM T. CHRISTMAS.
